(57) CLAIM

The ornamental design for a pacifier as shown and described.

DESCRIPTION

FIG. 1 is a front, top perspective view of a pacifier, showing our new design;

FIG. 2 is a bottom elevational view of FIG. 1;

FIG. 3 is a front view of FIG. 1;

FIG. 4 is a rear view of FIG. 1;

FIG. 5 is a right side view of FIG. 1;

FIG. 6 is a left side view of FIG. 1;

FIG. 7 is a front perspective view of FIG. 1; and,

FIG. 8 is a rear perspective view of FIG. 1.

In the drawings, the broken lines depict portions of the pacifier that form no part of the claimed design.
